UNITED STATES PATENT OFFICE

CHARLES SAMUEL FRANKLIN AND BERTRAM JOHN WITT, OF LONDON, GEORGE MAURICE WRIGHT, OF CHESTERFIELD, AND SIDNEY BERTRAM SMITH, OF CHELMSFORD, ENGLAND, ASSIGNEES TO RADIO CORPORATION OF AMERICA, A CORPORATION OF DELAWARE

WIRELESS-TELEGRAPH RECEIVING SYSTEM

Application filed June 1, 1923, Serial No. 642,758, and in Great Britain January 15, 1923.

It is known that when a radiogoniometer is connected to two frame aerials as in the Bellini aerial, that direction of signals can be found by rotating the moving coil which is connected to a suitable receiver.

According to our invention we connect to a common pair of frames two or more radiogoniometers. Thus two or more stations which are in different directions with respect to the receiving station may be received independently on a common aerial irrespective of what their wave lengths may be. This apparatus was disclosed and broadly claimed in a copending application of Charles S. Franklin and Bertram J. Witt, Serial No. 626,423, filed March 20, 1923.

We may employ a special search coil which comprises two sections, wound at right angles to one another, each section forming part of a separate tuned circuit. The circuit of one section, which we will call the active section, is coupled to a receiver circuit, while that of the other section, which we will call the compensating section, includes an adjustable resistance to compensate for the reactive effect of the receiver.

Alternatively we may provide a pair of radiogoniometers for each receiver, the field coils of the first radiogoniometer being connected to the receiving antennæ while the field coils of the other are connected to artificial serials possessing the same characteristics as the receiving antennæ.

The search coils are connected in series or parallel and are coupled to a receiver through the usual tuning circuits; these search coils are mechanically coupled together and their windings are in opposition so that the coupling between the first search coil and the receiving antennæ is anti-coupled via the artificial aerial.

Our invention is illustrated by the accompanying diagrams:

Fig. 1 is a simple arrangement conforming to the invention.

Fig. 2 is an arrangement similar to Fig. 1 but including means for reducing the reaction effects between the several circuits.

Fig. 3 is a modification.

Figs. 4 and 5 are modifications disclosing

an arrangement for modifying the directional characteristics of the several receiver devices.

Figs. 6 and 7 are modifications combining the compensating means of Fig. 2 with the directional systems of Figs. 4 and 5 respectively and,

Figs. 8 and 9 are modifications combining the anti-coupling means of Fig. 3 with the directional systems of Figures 4 and 5 respectively.

In Figure 1, A, A¹, represent the loop aerials (preferably aperiodic) of a Bellini Tosi system, B, B¹, are the two receivers, C, C¹, being the field coils of the two radiogoniometers and D, D¹, the search coils the circuits of which can be tuned by means of condensers E, E¹, and include primaries F, F¹, of transformers, by which the signals are conveyed to receiving circuits G, G¹.

With such an arrangement signals from two stations which lie in different directions may be received in the two circuits G, G¹.

The efficiency, however, of this simple system depends upon the tightness of the couplings between the circuits and upon the amount of reaction between the circuits. In order to receive on either circuit independently with the greatest efficiency the coupling should be as tight as possible but inasmuch as the reaction between the circuits increases with the tightness of the coupling, the movement of one of the search coils of one of the radiogoniometers will impair the efficiency of reception of the other radiogoniometer.

Figures 2 and 3 show arrangements in which reaction is avoided so that both receivers may be arranged to act with the greatest possible efficiency without the movements of the search coil of one radiogoniometer affecting the other. In other words, each receiver is independent of the other.

In Figure 2 the search coil of circuit B comprises two sections D, d, wound at right angles to one another; the active section D is connected as before to a tuning condenser E and the primary F by which the circuit is coupled to the receiving circuit G, while the compensating section d is connected in a tuned circuit comprising a tuning condenser

e, and inductance *f* and an adjustable resistance *r* to compensate for the reactive effect of the receiver. Similarly the search coil of receiver B^1 is composed of two sections, the active section D^1 and the compensating section d^1 being connected to condenser c^1 and inductance f^1 and resistance r^1 .

The two tuned circuits of each search coil system should be made exactly equal in all respects, namely, inductance, capacity, resistance and mutual inductance to the aerial circuit. Also there should be no mutual inductance between the two sections of the search coil.

It is found that with such a system the reactive effect of one radiogoniometer upon the other will be constant no matter what may be the position of either search coil.

In Figure 3 each receiver comprises two radiogoniometers, $C D$ and $C^1 D^1$ being connected as before to the loop aerials, A , A^1 , while $c H$ and $c^1 H^1$ are similarly connected to artificial aerials a , a^1 , possessing the same characteristics as the loop aerials A , A^1 . The search coils $D H$ are connected in series in a circuit including as before tuning condensers and primaries of transformers by which their circuits are coupled to the receiving circuits G . $D^1 H^1$ are connected in a similar circuit coupled to G^1 . The coils D and H and also the coils $D^1 H^1$ are mechanically connected and are arranged in such a manner that the couplings between the coils D , D^1 and the receiving aerials are anti-coupled via the artificial aerials. As a result the reactive effect of either of the circuits $D E H F$ and $D^1 E^1 H^1 F^1$ on the other is reduced to zero.

Thus with the arrangement shown in Figures 2 and 3 it is possible to use tightly coupled radiogoniometers and to receive efficiently on the two receivers B , B^1 , simultaneously and also it is possible to rotate the polar curve of either without disturbing the other.

Figure 4 shows an arrangement by which a heart-shaped diagram may be obtained on each receiver. The centre points of the fixed coils C , C^1 of the two radiogoniometers are connected to earth through inductances L^1 , L^2 . The circuit of search coil D is tuned to one of the waves to be received and is coupled through the tuned circuit K to the inductance L^1 and also through an intermediate tuned circuit M to the receiving circuit G . Similarly the circuit of the search coil D^1 is tuned to a second wave to be received and is coupled through a tuned circuit K^1 to the inductance L^2 and through a tuned intermediate circuit M^1 to the receiving circuit G^1 . Each of the receivers is therefore worked by a circuit which is associated with the two frames, A , A^1 , and also with a plain aerial, namely that which includes the inductances L^1 , L^2 . The whole system therefore gives a

heart-shaped diagram provided the amplitude and phase of the potentials induced in the circuits of D , D^1 , for the different waves respectively are correct. The amplitudes can be easily adjusted by means of the couplings while the phases for each wave can be adjusted by tuning the circuits K and K^1 respectively, resistances R , R^1 being included in these circuits so that the adjustments may not be too critical. This method of phase adjustment, that is, by varying the tune of an intermediate circuit, is a convenient means for obtaining the desired result, but any method of phase shifting may be employed instead.

If the couplings in the radiogoniometers and those of the plain aerial circuit are small either of the radiogoniometers can be adjusted without seriously affecting the setting of the other.

A critical value of the couplings which is dependent on the difference between the wave lengths being received may be employed. If this difference is a few per cent or more of either wave length no diminution in the strength of the signals will be noticed, but if the difference is very small or zero the couplings must be weakened below the optimum in order to obtain complete independence of the two radiogoniometers.

Or the arrangement shown in Figures 2 or 3 may be employed.

Figure 5 shows an arrangement which is similar to that of Figure 4 except that the radiogoniometers are removed to a distance from the frames and are connected to them by cables N , N^1 . Here each frame is closed and the frames are coupled to the fixed coils of the radiogoniometers by transformers T , T^1 , while the plain aerial is formed by connecting the middle point of the bottom limb of each frame to earth through a resistance O and inductance P in parallel therewith, this inductance being coupled to the middle points of the secondaries of the transformers T , T^1 .

The systems shown in Figures 6 and 7 are substantially similar to the systems shown in Figures 4 and 5 respectively. Detailed description of these circuit arrangements and their operation is therefore deemed unnecessary except to note that the compensating coils d , D and d^1 , D^1 of Figure 2 are used to couple the respective receiver circuits to the goniometers to prevent reaction of one circuit on the other.

Figures 8 and 9 are substantially similar to and operate in the same manner as Figures 4 and 5 respectively. In these modifications the artificial aerials shown and described in connection with Figure 3 are combined with the directive systems shown in Figures 4 and 5. In this manner coupling between the separate aerial systems and associated coils are anti-coupled via the artificial aerials.

Having described our invention, what we claim is:

1. The combination of two directional antenna circuits, two radiogoniometers each comprising a pair of field coils and a search coil, one field coil of each radiogoniometer being connected to each antenna circuit and a separate signaling circuit connected to each search coil. 5
2. The combination of two loop antenna circuits, a pair of radiogoniometers each consisting of a pair of angularly disposed field coils and a movable search coil, means for connecting one field coil of each radiogoniometer to each antenna circuit and a separate signal receiving circuit connected to each search coil. 10
3. The combination of two radio frequency directional antenna circuits, a plurality of radiogoniometers each comprising a pair of field coils and a search coil having one field coil connected to one antenna circuit and the other field coil connected to the other antenna circuit, a signaling circuit connected to each 15 search coil and means associated with each signaling circuit for compensating for reactive effects. 20
4. The combination of two directional antenna circuits, a plurality of radiogoniometers each including a pair of field coils having one coil connected to each antenna circuit, a search coil for each radiogoniometer and a separate signaling circuit connected to each search coil and an artificial antenna connected 25 to each search coil. 25
5. The combination of two directional antenna circuits, a plurality of radiogoniometers each including a pair of field coils and a search coil, a separate signaling circuit connected to each search coil, a pair of artificial antennæ and a plurality of radiogoniometers associated with said artificial antennæ the search coil of each of said last named radiogoniometers being connected to one of said 40 signaling circuits. 45
6. The combination of two directional antenna circuits, a plurality of radiogoniometers each including a pair of field coils and a search coil having one field coil connected to one antenna circuit and the other field coil connected to the other antenna circuit, two artificial antenna circuits with characteristics substantially similar to those of said first named conducting circuits, a plurality of radiogoniometers each having a pair of field coils and a search coil and each having one field coil connected to one artificial circuit and the other field coil connected to the other artificial circuit, a plurality of signaling circuits each connected to a search coil of one of said first named radiogoniometers and to a search coil of said second named radiogoniometer and means for mechanically connecting the search coils connected to the 45 same signaling circuit. 65
7. The combination of two directional antenna circuits, a plurality of radiogoniometers each including a pair of field coils having one coil connected to each antenna circuit, a search coil for each radiogoniometer, a separate signaling circuit associated with each search coil, and means including tuning means associated with each of said search coils for compensating the reactive effects caused thereby. 70
8. The combination of two directional antenna circuits, a plurality of radiogoniometers each including a pair of field coils having one coil connected to each antenna circuit, a search coil for each radiogoniometer, a separate signaling circuit associated with each search coil, and coils associated with each of said search coils in such a manner as to prevent reaction between the signaling circuits. 75
9. The combination of two directional antenna circuits, a plurality of radiogoniometers each including a pair of field coils having one coil connected to each antenna circuit, a search coil for each radiogoniometer, a pair of circuits substantially electrically equal to said antenna circuits, a plurality of radiogoniometers associated with said last named circuits and a plurality of receiving circuits each associated with a search coil of one of said first named radiogoniometers and with a search coil of one of said last named radiogoniometers. 80
10. The combination of two loop aerials, a plurality of conducting circuits associated with said aerials, a plurality of radiogoniometers each having a field coil associated with each of said conducting circuits, and a receiving circuit associated with the search coil of each of said radiogoniometers. 85
11. The combination of two loop aerials, a plurality of conducting circuits, a plurality of radiogoniometers each having a field coil connected in series with each of said conducting circuits, a search coil for each radiogoniometer, and a receiving circuit associated with each search coil. 90
12. The combination of, a plurality of coaxial directional antennæ circuits, a coil in each of said circuits, a radio frequency signaling circuit associated with each of said antennæ circuits, and means including a rotatable search coil for each signaling circuit for coupling said signaling circuit to all of said antennæ circuits to permit independent signaling in each signaling circuit. 95
13. The combination of two radio frequency directional conducting circuits, a plurality of radiogoniometers each comprising a pair of field coils and a search coil, one field coil of each of said radiogoniometers being coupled to one conducting circuit and the other field coil being coupled to the other conducting circuit, a signaling circuit connected to each search coil and means associated with 125

each signaling circuit for compensating for reactive effects, said means comprising a coil in angular relation to the search coil.

14. The combination of a plurality of directional aerial circuits, a plurality of radiogoniometers each including a plurality of field coils one of each of which is coupled to each of said aerial circuits, a search coil for each radiogoniometer and a signaling circuit connected to each search coil, a coil at right angles to each search coil and a separate circuit containing tuning elements connected to each of said last named coils.

15. The combination of two directional aerial circuits, a plurality of radiogoniometers each connected to each directional aerial circuit, a receiver connected with the search coil of each of said radiogoniometers and means for preventing interference between signals in said receivers including including inductances angularly disposed with respect to said search coils.

16. Apparatus as claimed in claim 15 in which each of said inductances are included in a tuned circuit.

17. The combination of two directional antenna circuits, a non-directional antenna circuit associated with said circuits, a plurality of radiogoniometers each having a pair of field coils and a search coil, one of said field coils being connected to one of said directional circuits and the other being connected to the other directional circuit, and a plurality of signaling circuits each connected to the search coil of one of said radiogoniometers and to said non-directional antenna circuit.

18. The combination of two directional receiving antennæ, a non-directional receiving antenna, a plurality of radio receiving circuits, means for connecting the latter to said non-directional antenna and a radiogoniometer for connecting each receiving circuit to each of said directional antenna whereby independent signals from different directions may be received in each receiving circuit simultaneously.

19. The combination of a plurality of directional aerial circuits, a plurality of radiogoniometers each of which are connected to each of said aerial circuits, a separate receiver connected to each of said radiogoniometers, and a vertical aerial associated with said radiogoniometers, and said receivers.

20. The combination of a plurality of frame aerial circuits, a plurality of radiogoniometers each associated thru field coils with all of said frame aerials, a separate receiver associated with each of said radiogoniometers, and means for impressing a vertical aerial effect on each of said receivers.

21. The combination of a pair of angularly disposed frame aerials, a plurality of radiogoniometers each having a field coil connected with each of said frame aerials, a

search coil coupled with the field coils of each of said radiogoniometers, a separate receiver connected to each search coil, means for preventing interference between signaling currents in said receivers including a tuned inductance angularly disposed with reference to each of said search coils, and a vertical aerial coupled to each of said search coils.

CERTIFICATE OF CORRECTION.

Patent No. 1,773,355.

Granted August 19, 1930, to

CHARLES SAMUEL FRANKLIN ET AL.

It is hereby certified that error appears in the printed specification of the above numbered patent requiring correction as follows: Page 3, line 54, claim 6, for "conducting" read antenna; line 62, before "said" insert one of, and line 63, for "radiogoniometer" read radiogoniometers; and that the said Letters Patent should be read with these corrections therein that the same may conform to the record of the case in the Patent Office.

Signed and sealed this 9th day of December, A. D. 1930.

M. J. Moore,
Acting Commissioner of Patents.
